227,038

COMBINED PEN AND HOUSING FOR THERMOMETER OR THE LIKE

Harold F. Bajusz, Woodridge, N.J., assignor to Accutec Inc., Wallington, N.J.

Filed May 14, 1971, Ser. No. 143,749

Term of patent 14 years

Int. Cl. D19—06

U.S. Cl. D74—17 B

FIG. 1 is a side elevational view of a combined pen and housing for a thermometer or the like showing my new design;

FIG. 1a is a top plan view thereof;

FIG. 1b is a bottom plan view thereof;

FIG. 2 is an exploded front view;

FIG. 3 is a front elevational thereof as it appears with the cap separated from the pen; and

FIG. 3a is a top plan view thereof as seen looking down from the writing tip.

The dominant features of my design reside in the specific writing tip portion as shown in FIGS. 2 and 3.

I claim:

The ornamental design for a combined pen and housing for a thermometer or the like, as shown and described.

References Cited

UNITED STATES PATENTS

D. 153,763	5/1949	Campbell	-----	D74—20
3,033,213	5/1962	Joss	-----	D74—20

OTHER REFERENCES

A.S. Aloe Co., Hospital Instruments, etc. Cat. © 1942, p. 193, Item #75A170.

Premium Practice, October 1968, p. 119, center right pentel pen item.

JOEL STEARMAN, Primary Examiner

L. J. PERLSTEIN, Assistant Examiner